United States Patent Office

Des. 218,751
Patented Sept. 22, 1970

218,751

AUTOMATIC CASSETTE PROCESSOR

Clarence D. Zierhut, Granada Hills, Calif., assignor to
Data Instrument Company, Sepulveda, Calif., a corpora-
tion of California

Filed July 9, 1969, Ser. No. 18,119

Term of patent 14 years

Int. Cl. D14—01

U.S. Cl. D26—14

FIG. 1 is a perspective view of the processor embodying my new design illustrating the top, front and right side of the processor;

FIG. 2 is a view of the processor illustrating the left side of the processor; and

FIG. 3 is a view of the processor illustrating the rear of the processor.

I claim:

The ornamental design for an automatic cassette processor, substantially as shown and described.
